UNITED STATES PATENT OFFICE.

JOSEPH S. BLINN, OF NEW HAVEN, CONNECTICUT, ASSIGNOR TO THE SCOVILL MANUFACTURING COMPANY, OF WATERBURY, CONNECTICUT.

DESIGN FOR A BADGE.

SPECIFICATION forming part of Design No. 25,554, dated June 2, 1896.

Application filed April 27, 1896. Serial No. 589,325. Term of patent 3½ years.

To all whom it may concern:

Be it known that I, JOSEPH S. BLINN, of New Haven, in the county of New Haven and State of Connecticut, have invented a new 5 Design for Campaign-Badges; and I do hereby declare the following, when taken in connection with the accompanying drawings and the letters of reference marked thereon, to be a full, clear, and exact description of the same, 10 and which said drawings constitute part of this specification, and represent, in—
15 This invention relates to a design for campaign-badges; and the design consists in the configuration and ornamentation hereinafter described, and shown in the accompanying illustration.

The design consists of a button the face of 20 which is circular and ornamented by a bell A in relief, and upon the bell is a raised naked arm B, holding a hammer C.

I claim—

The design for a campaign-badge as herein 25 shown and described.

In testimony whereof I have signed this specification in the presence of two subscribing witnesses.

JOSEPH S. BLINN.
